TRENCHER

Vincent S. Penote, Cleveland, Ohio, assignor to
The Cleveland Trencher Company, Cleveland,
Ohio, a corporation of Ohio

Application March 7, 1945, Serial No. 581,461

5 Claims. (Cl. 37—97)

1

The present invention relates to an excavating machine and particularly to an excavating machine of the type in which a wheel provided with excavating buckets is used for digging trenches and the like. The invention is particularly concerned with improvements in the machine to increase its capacity. This, therefore, is the general object of the present invention.

Excavating machines of the type with which this invention is concerned, generally comprise a vehicular frame which supports an engine and various driving mechanism. At one end of the frame a mast is provided which carries a support on which is mounted an excavating wheel, the arrangement being such that the wheel overhangs the frame of the machine. In the past, considerable attention has been given to the excavating wheels to obtain rigidity of the structure, and at the same time reduce the weight of the wheel to a minimum. An object of the present invention is to increase the dirt-carrying capacity of the excavating wheel without sacrificing the advantages of rigidity and lightness in weight.

Other objects of the invention will become more apparent from the following description, reference being had to a preferred embodiment of the invention illustrated in the accompanying drawings. The essential features of the invention will be summarized in the claims.

In the drawings, Fig. 1 is a side elevation of an excavating machine embodying my invention; Fig. 2 is a fragmentary section taken through the excavating wheel as indicated by the line 2—2 on Fig. 1; and Fig. 3 is a sectional view similar to Fig. 2, but illustrating a modified arrangement.

The excavating machine as illustrated in Fig. 1 comprises, in general, a main frame 10 mounted on a pair of tractor belts, one of which is shown at 11. These belts are driven by a motor 12 which is supported at the forward end of the frame. At the rear of the frame there is provided an upwardly extending guideway 15, slidably mounted in which is a support for a carriage 16. Pivoted, as at 17, to the carriage is an outwardly extending boom or digging wheel frame 18.

The support or digging wheel frame 18 is raised, lowered and swung about its pivot 17 by cables 20 and 21. The cable 20 serves to raise and lower the carriage 16, thus controlling the position of the inner end of the frame, and the cable 21 controls the outer end of the frame. The cables are operated by winding drums, indicated at 22, and which are driven by the motor 12.

2 A digging wheel 19 is rotatably supported by the frame 18 and comprises a pair of spaced rings 25 which are secured together by a series of U-shaped digging buckets 26. The wheel is supported by a plurality of rollers, two of which are shown at Fig. 1 at 27 as engaging the inner flanges of the inner edges of the rings 25. One of the rollers 27 is carried by the support 18 and the other by bracing 28 which is secured 10 to said support. The digging wheel is rotated by the motor 12 through a suitable transmission unit 30, drive chain 31, which drives a sprocket 32 secured to a shaft 33. Also secured to the shaft 33 are a pair of sprockets, one of which is 15 shown at 34 as engaging pins or teeth-like formations 35 carried by the digging wheel rings 25.

The arrangement is such that the digging wheel 19 may be lowered to the position indicated by the dot and dash lines of Fig. 1 and rotated in 20 the direction of the arrow for excavating purposes. Dirt or other material is excavated and gathered by the buckets 26, which carry such material upward to the top of the wheel where it falls by gravity onto a belt conveyor 36. This 25 conveyor is supported by and extends transversely of the support 18, and is driven from the shaft 33 by a suitable driving mechanism, generally indicated at 37.

The excavating buckets 26, as shown in Fig. 2, 30 comprise U-shaped members 40 of the legs 41 of which abut the periphery of respective rings 25 of the digging wheel 18, so that the inner walls 42 thereof form substantially continuations of the inner faces of the respective digging wheel rings 25. The walls of the buckets are tapered 35 slightly so as to facilitate the gravitational movement of the contents thereof as each bucket reaches the upper reach of its path during the movement of the wheel.

To increase the capacity of each digging bucket, 40 I have provided a stationary arc-plate or channel. This plate or channel is shown at 45 in Fig. 2, arranged so that its legs 46 form continuations of the inner faces of respective digging 45 wheel rings 25. The channel 45 is secured to the braces 28 heretofore described as being part of the wheel support 18. The channel 45 is positioned at the forward end of the digging wheel and extends for substantially a quarter of the circumferential distance of the wheel, the arrangement being such that it forms an inner wall for the buckets throughout substantially the entire upward travel thereof. Preferably, the channel 45 extends over about a quadrant of the wheel 50 and coacts simultaneously with a plurality of

buckets. The material which is excavated and gathered by the buckets extends into the channel 45 and is carried upward by bucket backs 50. These may comprise a plate such as shown at 50A in Fig. 2 and suitable tine-like extensions 50B, or the plate itself may be extended as indicated by the line 50C in Fig. 3.

From the foregoing description, it will be seen that I have materially increased the amount of material which may be handled by the buckets, whereas the actual size of the excavating buckets remains comparatively small. The capacity being controlled is the distance from the outer face of the bucket to the inner face of the channel plate 50. It will likewise be noted that the walls of the channel plate are tapered to facilitate movement of dug material therethrough.

I claim:

1. In an excavator, a support, an excavating wheel rotatably mounted on said support and comprising spaced annular rings, a series of excavating buckets connecting said rings and extending outward therefrom, a channel member carried by said support within the wheel and having its legs forming inward extensions of the rings.

2. In an excavator, a support, an excavating wheel rotatably mounted on said support and comprising spaced annular rings, a series of excavating buckets secured to and bridging said rings and radially outward therefrom, an elongated arculate channel secured to said support and having its legs forming inward extending continuations of said rings.

3. In an excavator, a support, an excavating wheel rotatably mounted on said support and comprising a pair of spaced annular rings, a series

of spaced excavating buckets comprising U-shaped members having the legs thereof secured to the respective rings and extending radially outward therefrom with the open portion of the U adjacent the periphery of the wheel, a channel shaped arc carried by said support and having its legs substantially comprising inward extensions of the rings, and means on said buckets and extending between the rings into said channel to move dirt therealong.

4. In an excavator, a support carried thereby, an excavating wheel rotatably mounted on said support and comprising a pair of spaced annular rings, a series of circumferentially spaced excavating buckets connecting said rings and extending radially outward therefrom and having an open face adjacent the periphery of said wheel, a channel-shaped arc plate carried by said support and having the legs thereof extending toward respective rings and having their inner faces in substantial alignment with the inner faces of respective rings, and means to rotate said wheel.

5. In an excavating machine, a support, an excavating wheel mounted thereon, said wheel comprising a pair of spaced annular rings, a plurality of circumferentially spaced buckets secured to and extending radially outward from said rings, and a channel-shaped member carried by said support and having the edges of the legs thereof coacting with the inner edge of respective rings and diverging inwardly toward the web of the channel, and means carried by said buckets and extending into said channel to move dirt therethrough.

VINCENT S. PENOTE.
